UNITED STATES PATENT OFFICE

91,836

DESIGN FOR A COMBINATION RURAL MAIL BOX AND SUPPORT THEREFOR

Roman J. Miller, Hollywood, Calif.

Application June 5, 1933, Serial No. 48,281

Term of patent 14 years

To all whom it may concern:

Be it known that I, ROMAN J. MILLER, a citizen of the United States, residing at Hollywood, in the county of Los Angeles and State of California, have invented a new, original, and ornamental Design for a Combination Rural Mail Box and Support Therefor, of which the following is a specification, reference being had to the accompanying drawing, forming a part thereof.

Fig. 1 is a side elevational view of the article showing my new design,

Fig. 2 is a cross-sectional view on the line of section on Fig. 1, and

Fig. 3 is a front elevational view thereof.

The dominant features of my new design are the general outlines of the article, including the support, and the surface ornamentation on the various parts thereof.

I claim:

The ornamental design for a combination rural mail box and support therefor, substantially as shown and described.

In testimony whereof I have signed my name to this specification.

ROMAN J. MILLER.
